UNITED STATES PATENT OFFICE.

COLEMAN SUTTON, OF JEFFERSONVILLE, INDIANA.

DIRIGIBLE HEADLIGHT.

Application filed July 18, 1925. Serial No. 44,474.

This invention relates to the class of inventions known as dirigible headlights, and it is directed to an improved structure wherein the headlights are mounted for turning movement upon vertical axes, together with means for providing an operative connection of the same with the steering gear so that the lights will be automatically angled in parallelism with the front 10 wheels to cause the light rays to follow or be directed upon the path of travel, at all times.

My principal object is to generally improve upon structures of this class by providing one of comparative simplicity and 15 durability wherein the details are, themselves, novel, and arranged in a novel association assuring the production of a practical arrangement which is positive in operation, and otherwise efficient in its accomplishments.

Other features and advantages of the invention will be more specifically pointed out in the following description and appended 20 claims.

In the accompanying drawings forming a part of this application, and in which like numerals are employed to designate like parts throughout the same:

Figure 1 is a front elevation of a conventional automobile equipped with a headlight structure constructed in accordance with the present invention.

Figure 2 is a top plan view showing the relative association of parts.

Figure 3 is an enlarged elevational and sectional view showing more in particular the manner in which the headlights are mounted.

Figure 4 is a detail section taken approximately upon the plane of the line 4-4 of Figure 3.

Figure 5 is an enlarged top plan view of a part of the mechanism showing the construction more plainly.

Figure 6 is a detail perspective view of the connection of the device with the steering rod showing how it clears the existing steering gear when swung to its extreme right hand position.

Each headlight is the same in construction and is mounted in the same way. For clearness, the headlight and manner of mounting will be described in the singular. In this connection attention is invited to Figure 3 wherein it will be seen that the reference character 1 designates a conventional

fender brace such as is found on the commonly marketed Ford automobile. As is well known, this brace is provided adjacent the chassis with an opening in which the usual stationary standard of the common headlight is received. In accordance with the present invention that standard is removed and a relatively short standard 2 is substituted. This new standard is screw threaded at 3 and passed through the usual opening in the brace 1 as shown. Retaining nuts 4 are then threaded in place to hold the standard firmly in position. On its upper end the standard is provided with a sectional 65 socket 5 provided at its front with an enlarged round hole 6. Fitted into this socket is a ball joint 7 carrying a stem 8 threaded at its front. The stem is movable universally in the hole 6 and the threaded end is 70 tapped into a socket formed in a bearing block 9. By preference, a set-screw 10 is employed to afford a good connection between this stem and block. Moreover, a set-screw 30 is employed on the top of the socket 75 to engage the ball portion on the inner end of the stem. The headlight, generally represented by the reference character 11, is provided with a shaft including a smooth 80 portion 12, this portion being rotatably received in the bearing opening in the block. The shaft is then reduced and screw threaded for reception of a clamping nut 13. That portion of the shaft depending below the 85 nut is further reduced as at 14 and a removable crank arm 15 is connected therewith by a set screw 31 as more plainly seen in Figure 4. This arm extends at right angles and in a horizontal manner. The shaft is, of course, provided with a stop flange 16 which rests rotatably on the top of the bearing block. This is deemed to be a novel 90 mounting for headlights, and in this connection I call attention to the fact that the headlights together with the associated details 95 may be adjusted up and down, or from side to side owing to the ball and socket joint described so that the two headlights may be properly aligned with each other. This is a 100 feature upon which emphasis is to be laid, particularly so because the headlights may be tilted up or down to throw the rays of light at any convenient distance in front of the machine.

Attention is now directed to Figure 6 110 wherein it will be seen that the reference character 17 designates the lower end of

the customary steering rod turned by the hand wheel (not shewn). The reference character 18 designates the operating crank arm, and 19 one of the horizontal rods of the customary steering gear. Fastened to the end of the rod 17 is an angular bracket 20. This carries a depending arm 21, on the lower end of which is a ball connector 22, the same being connected in the fork 23 on one end of an operating link 24.

Referring now to Figure 5 it will be seen that this link is provided on its opposite end with a somewhat similar fork 25, this being disposed in a horizontal plane by twisting the link as shown. The last named fork is connected, through the medium of a ball and socket connection with a transverse operating bar 26, this bar being provided at its opposite ends with forks 27 connected with ball connectors on the lower down turned ends of a pair of substantially right angular rods 28. On the horizontal forward ends of the rods 28 are adjustably mounted forks 29 (see Figure 4) which are connected with the adjacent arms 15.

From the foregoing description it is obvious that as the steering rod 17 is turned upon its axis, the link 24 is moved in a substantially horizontal plane through the medium of the connection afforded by the angle bracket 20 and connecting arm 21. By so moving the same it is obvious that a corresponding movement is imparted to the operating bar 26, which, through the medium of the rod 28 serves to rotate the lights from side to side to angle them in accordance with the direction of movement of the front wheels.

One feature to be borne in mind is that the present structure is such that it can be installed and associated with the existing details of a Ford automobile without requiring extensive alteration. The parts are so proportioned that they do not interfere in any way with the usual steering gear, and there is little or no liability of the parts binding by insufficient clearance, regardless of the angularity of the wheels assumed in making acute angular turns. The headlights are supported independently of the operating means from details which are believed to be novel, particularly so because of the fact that they can be connected with

the customary fender braces by simply removing the usual headlight standards. The working parts are comparatively few, wear is reduced, and there is little possibility of failure of operation of any detail. These and other advantages have doubtless been made apparent by the foregoing description and drawing. Furthermore, the construction and arrangement would seem to be clear; therefore, a more lengthy description is thought unnecessary.

While the preferred embodiment of the invention has been shown and described it is to be understood that minor changes coming within the field of invention claimed may be resorted to if desired.

Having thus described the invention, what I claim as new and desire to secure by Letters Patent is:—

1. In a headlight structure of the class described, a standard adapted to be supported from a conventional fender brace, a socket at the top of said standard, a bearing block provided with a bearing opening, a stem adjustably connected with said block and having a ball connector on its end received in said socket, a retaining screw carried by the socket and engageable with the ball for supporting the bearing block in various adjusted positions, and a headlight including a shaft rotatable in the bearing opening of said block.

2. In a dirigible headlight structure, supporting standards, bearing blocks, universal and adjustable connections between the blocks and upper ends of the standards, headlights supported upon said blocks, said headlights embodying shafts rotatable in the bearing openings of the blocks, crank arms connected to the lower portions of the shafts, a pair of angular rods, the approximately horizontal portions of which are connected with said crank arms, a connection between the vertical portions of said rods, an operating link disposed at an angle to said connection and having universal connection with the intermediate portion of the connection, an angular attaching bracket for a steering rod, and a universal operating connection between the bracket and the adjacent end of said link.

In testimony whereof I affix my signature.
COLEMAN SUTTON.
